ANIMATED DISPLAY DEVICE

Gwynne Oscar Brown, Vancouver, British Columbia, Canada, assignor to Motion Displays, Inc., a corporation of New York

Application July 24, 1934, Serial No. 736,629
In Canada September 5, 1933

9 Claims. (Cl. 40—32)

This invention relates to animated display devices, and more particularly to animated display devices of the type in which an endless band or belt carrying advertising matter is moved back of a casing aperture.

In such devices it is common practice to tension the band about two or more rollers, one of which is power energized to give movement to the band, and to position electric lamps behind the band to accentuate the advertising matter carried thereby. Inasmuch, however, as the band is generally made from thin flexible material, such as paper, it has a tendency to stretch after being in use, and when this occurs the band slips as it passes over the rollers. Also it has been found that the heat generated by the lamps, if permitted to accumulate in the casing, constitutes a fire hazard. Furthermore, in such devices the band frequently creeps longitudinally along the rollers and is thus carried beyond the limits of the casing aperture, this creeping action of the band being due to the fact that the length of the band may vary from one edge to the other and or to the fact that the axes of rotation of the rollers may not be parallel.

An object, therefore, of the present invention is to provide such devices with means which prevents the band from slipping as it passes over the rollers.

Another object of the invention is to provide means which prevents heat from accumulating in the casing of such devices.

Still another object of the invention is to provide such devices with means which prevents the band from creeping longitudinally along the rollers as it is moved back of the casing aperture.

Still another object of the invention is to provide such devices with means for obtaining an increased advertising effect from a given number of moving parts.

In accordance with one feature of the present invention, slipping of the band as it passes over the rollers is prevented by means of a take-up device which acts automatically to tension the band and thus maintain it in frictional engagement with the rollers.

In accordance with another feature of the invention, means are provided for circulating the air in the casing to dissipate the heat generated by the lamps and other power operated devices.

In accordance with still another feature of the invention, means is provided which is capable of being adjusted so as to cause the band to have a tendency to creep longitudinally along the

rollers in either direction so that any normal tendency the band has of creeping along the rollers may be counteracted.

In accordance with still another feature of the invention, the rollers which ordinarily are only used to move the band, are utilized to operate display devices upon which goods to be advertised may be placed and thus increase the advertising effect from a given number of moving parts.

For a clear understanding of the invention, reference may be made to the accompanying drawings. In the drawings, however, the invention is shown merely in preferred form and by way of example, but obviously many changes and variations may be made therein and in its mode of operation which will still be comprised within its spirit. It is, therefore, to be understood that the invention is not limited to any specific form or embodiment except in so far as such limitations are specified in the claims.

Referring to the drawings:

Fig. 1 is a front elevational view with a portion broken away of a device embodying the principles of the present invention;

Fig. 2 is a plan view, the view being taken along the line 2—2 of Fig. 1; and

Fig. 3 is a perspective view having the front wall of the casing removed to more clearly show the relation of the various parts of the mechanism.

As shown, the mechanism is mounted within a casing 10, the front wall of which is provided with an aperture 11 behind which an endless belt or band 12 carrying advertising matter is moved and the cover 13 of which is hinged thereto to permit ready access to the mechanism.

The band 12 is trained about a drive roller 14 and an idler roller 15, the opposite ends of the drive roller 14 being provided with trunnions 16 which are journaled in one end of an oblong supporting frame 17 and the opposite ends of the idler roller 15 being provided with trunnions 18 which are journaled in the opposite end of the framework 17. The drive roller 14 is power operated to give movement to the band 12 by a motor and gear reduction mechanism 19 which is operatively connected to the trunnion carried by the lower end of the drive roller 14.

The framework 17 is also provided with two sockets 20 and 21 in which lamps 22 and 23 respectively may be inserted when it is desired to accentuate the advertising matter on the band 12 as it passes behind the aperture 11, and to maintain the lamps out of contact with the band 55.

to avoid the possibility of the band being scorched or burned by the heat generated by the lamps the frame work 17 is bent or slightly curved in a longitudinal direction.

5 The power for driving the motor as well as for lighting the lamps 22 and 23 is supplied from any convenient source through conductors 24 and 25 and a hand operated switch 26.

To prevent the heat generated by the lamps 10 22 and 23 and the motor and gear reduction mechanism 19 from accumulating in the casing 10 to the extent where it would constitute a fire hazard, means are provided for circulating air therethrough, and to this end a fan 27 is mounted 15 on the armature shaft 28 of the motor.

To prevent the band from slipping as it has a tendency to do after being in use, means are provided for maintaining it in frictional engagement with the rollers 14 and 15, and to this end 20 a tensioning roller 30 is journaled in the outer end of a gate member 33 by means of trunnions 31 which extend outwardly from the opposite ends thereof. The inner end of the gate member is pivotally secured to the central portion of the 25 frame work 17 by means of a rod 32, and a spring 34 acts to urge the tensioning roller 30 against the band to tension it and thus maintain it in frictional engagement with the rollers 14 and 15. One end of the spring is secured to the gate member 33 and the other end thereof is secured to one end of an arm 35 carried by the frame work 17. The other end of the arm 35 is secured to the frame work 17 by means of a stud 36, this arrangement being provided to permit the tension 30 in the spring 34 to be adjusted to a desired value.

To prevent the band 12 from creeping longitudinally along the rollers as it moves behind the aperture 11, means are provided for tilting the axis of rotation of one of the rollers over which 40 the band passes into and out of parallel relationship with respect to the axis of rotation of the other rollers. In the present embodiment of the invention means are provided for tilting the axis of rotation of the tensioning roller 30 into 45 and out of parallel relationship with respect to the axis rotation of the drive roller 14 and the idler roller 15, and to this end the upper arm of the gate member 33 is divided into two sections 50 37 and 38, the outer section 38 in which the trunnion 31 carried by the upper end of the tensioning roller 30 is journaled comprising an adjusting link which is secured, as by a stud 39, to the inner section 38. The opening 43 through 55 which the stud 39 passes is elongated to permit the position of the link 38 and hence the axis of rotation of the tensioning roller 30 to be adjusted. Under such conditions, if the band 12 has a normal tendency to creep as it is moved behind the casing aperture 11, the axis of rotation 60 of the tensioning roller 30 may be tilted until this tendency is counteracted and the band runs evenly over the rollers.

To increase the advertising effect from a given 65 number of moving parts the upper trunnion 16 of the drive roller 14 and the upper trunnion 17 of the idler roller 15, as shown in Fig. 1, may be provided with shaft like extensions 41 and 42 respectively which extend upwardly through suitable openings in the cover 13 and which carry 70 turntables 43 upon which goods to be advertised may be placed.

The ends of the window or aperture 11 are provided with grooves 44 in which shutters 45 of 75 selected widths may be disposed so as to pro-

vide a window or aperture of adjustable width for the purpose of making it correspond with bands of varying width.

Having thus described my invention, I claim:

1. In an advertising device, the combination 5 of a cabinet having an aperture therein, a plurality of rollers positioned in said cabinet, an endless band trained about said rollers, means for effecting rotation of said rollers for moving said band transversely behind said aperture, and 10 movable display devices carried by said rollers.

2. In an advertising device, the combination 15 of a cabinet having an aperture therein, a plurality of rollers positioned in said cabinet, an endless band trained about said rollers, means for effecting rotation of said rollers for moving said band transversely behind said aperture, means for maintaining said band under tension, and 20 movable display devices carried by said rollers.

3. In an advertising display device, the combination 25 of a cabinet having an aperture therein, a plurality of rollers positioned in said cabinet, an endless band trained about said rollers, means for effecting rotation of said rollers for moving said band transversely behind said aperture, means for maintaining said band under tension, means for preventing said band from creeping longitudinally along said rollers during movement thereof, and movable display devices carried 30 by said rollers.

4. In an advertising display device, the combination 35 of a cabinet having an aperture therein, a plurality of rollers positioned in said cabinet, an endless band positioned about said rollers, electric lamps positioned within said casing and behind said band, an electric motor operatively connected to one of said rollers for effecting rotation thereof to move said band transversely behind said aperture, means for dissipating heat 40 created by said lamps and said motor, means for maintaining said band under tension, means for preventing said band from creeping longitudinally along said rollers during movement thereof, and movable display devices carried by 45 said rollers.

5. In an advertising display device, the combination 50 of an elongated frame, a roller mounted at each end of said frame, a gate member pivotally mounted on said frame between the ends thereof, a roller carried by said gate, an endless band trained over said rollers, means for moving said band over said rollers, and means for swinging said gate about its pivotal connection to maintain the roller carried thereby in contact 55 with said band to render said band taut.

6. In an advertising display device, the combination 60 of an elongated frame, a roller mounted at each end of said frame, a gate member pivotally mounted on said frame between the ends thereof, a roller carried by said gate, an endless band trained over said rollers, means for moving said band, means for swinging said gate about its pivotal connection to maintain the roller carried thereby in contact with said band to 65 render said band taut, and means for tilting the angle of rotation of one of said rollers to prevent said band from creeping longitudinally along said rollers.

7. In an advertising display device, the combination 70 of an elongated frame, a roller mounted at each end of said frame, a gate member pivotally mounted on said frame between the ends thereof, a roller carried by said gate, an endless band trained over said rollers, means for moving 75

- said band, means for swinging said gate about its pivotal connection to maintain the roller carried thereby in contact with said band to render said band taut, and means for tilting the angle of rotation of the roller carried by said gate to prevent said band from creeping longitudinally along said rollers.
8. In an advertising display device, the combination of an elongated frame, a roller mounted at each end of said frame, a gate member pivotally mounted on said frame between the ends thereof, a roller carried by said gate, an endless band trained over said rollers, power means for driving one of said end rollers to move said band, means for swinging said gate about its pivotal connection to maintain the roller carried thereby in contact with said band to render said band taut, and means for tilting the angle of rotation of one of said rollers to prevent said band from creeping longitudinally along said rollers.
9. In an advertising display device, the combination of an elongated frame, a vertically disposed roller mounted at each end of said frame, 5 movable display devices carried by said end rollers, a gate member pivotally mounted on said frame between the ends thereof, a vertically disposed roller carried by said gate, power means for driving one of said end rollers to move said 10 band, means for swinging said gate about its pivotal connection to maintain the roller carried thereby in contact with said band to render said band taut, and means for tilting the angle of rotation of one of said rollers to prevent said 15 band from creeping longitudinally along said rollers.

GWYNNE OSCAR BROWN.
